UNITED STATES PATENT OFFICE

2,537,275

NONFOGGING GOGGLE

Robert L. Malcom, Jr., Chicago, Ill., assignor to
Chicago Eye Shield Company, Chicago, Ill., a
corporation of Illinois

Application April 9, 1945, Serial No. 587,235

2 Claims. (Cl. 2—14.7)

1

This invention has to do with goggles of the type now being used extensively in various industrial fields for protecting the eyes of the wearer against flying particles, etc. More particularly, the invention is concerned with an improved goggle which in addition to affording full vision and adequate protection is so constructed as to prevent fogging of the lens surfaces under the most unfavorable heat conditions.

The principal object of the invention is to provide a non-fogging goggle of new and improved construction.

Another object is to provide an improved goggle of the character described in which the exposed lenses are so constructed as to withstand blows of various sorts without fracture.

While the foregoing statements are indicative in a general way of the nature of the invention, other more specific objects and advantages will be apparent to those skilled in the art upon a full understanding of the construction of the goggle.

A preferred embodiment of the invention is presented herein by way of exemplification, but it will of course be appreciated that the invention is susceptible of embodiment in other structurally modified forms coming equally within the scope of the appended claims.

In the accompanying drawing:

Fig. 1 is a face view of a goggle constructed in accordance with the invention;

Fig. 2 is a top plan view of the goggle;

Fig. 3 is a side view of the same;

Fig. 4 is a horizontal section through one of the eye-cups of the goggle, taken on the line 4—4 of Fig. 1; and

Fig. 5 is a perspective view of the spacing ring positioned between the lenses in each eye-cup.

The goggle used to illustrate the invention comprises two individual face conforming eye-cups 10 and 11 which are connected together by a flexible bridge member 12 and are held in position on the wearer's head by an adjustable strap 13. As the two eye-cups are identical in construction it will only be necessary to describe one of them in detail.

The eye-cup 10 includes a tubular frame member 14 of generally circular cross section. This frame member—which may be molded from a suitable plastic material or constructed in any other way—terminates forwardly in a front edge 15 which is disposed in a plane at right angles to the axis of the member and terminated rearwardly in a rear edge 16 which is shaped to conform to the face of the wearer. Intermediate

the front and rear edges 15 and 16, and preferably in the portion of greatest rearward extent, the frame member 14 is provided with one or more air vents 17, which vents are covered over by fine wire screens 18 for preventing the entrance of any foreign particles.

A rim member 19 is screwed onto the outer surface of the front edge 15 of the frame member 14. This rim member projects forwardly a short distance beyond the front edge 15 and retains an outer lens 20 and an inner lens 21. The outer lens 20 completely closes off the front end of the eye-cup and is held against forward displacement by a small inturned flange 22 on the rim member 19. The inner lens 21 seats under spring pressure against the front edge 15 and is held in position by a resiliently compressible spacing ring 23, which ring is located between the two lenses about their margins. The ring 23, which is preferably made of thin sheet metal, with a split 24 at one point, and with a plurality of integral tongues 25 projecting from the plane of the ring at spaced points, provides an air space 26 between the lenses.

The rim member 19 is formed at points opposite the air space 26 with a plurality of openings 27, which openings serve to place the air space 26 in free communication with the air outside the eye-cup, thereby permitting circulation of such air into and out of the air space 26. These openings also afford conveniently located recesses for use in retaining the outer lens 20 and the spacing ring 23 whenever the rim member 19 is unscrewed from the frame member 14 to obtain access to the lenses for cleaning—the ring 23 for this purpose being provided at two or more points about its periphery with small radially projecting lugs 28 which enter and interlock with two of the openings 27. To insert the lugs 28 in the openings 27 it is merely necessary to momentarily constrict the ring 23 to a diameter small enough for the lugs to clear the threaded portion of the rim member 19, after which release of the ring will permit the same to spring back to its normal diameter.

The inner lens 21 is provided adjacent its periphery with a plurality of openings 29, which openings are arranged in a circle just inwardly of the front edge 15 of the frame member 14. These openings place the air space 26 between the lenses in communication with the air on the inside of the frame member and allow circulation of such air into and out of the space 26.

By providing a completely covering front lens, with a second lens behind the same, and with an

air space between the lenses, which air space is vented about its periphery to the outside of the eye-cup and is also separately vented to the inside of the same, a goggle structure is obtained which, in addition to offering unobstructed vision and adequate protection against eye injury, permits of a unique air circulation which has been found very effective in avoiding fogging of both lenses under conditions in which the ordinary goggle is unusable.

I claim:

1. In a goggle of the type described, a face conforming eye-cup, an inner lens, an outer lens, rim means for retaining said lenses over the front opening of said eye-cup with the outer lens completely closing off said front opening, spacer means between said lenses and spacing the same apart to provide an air space therebetween, said eye-cup being closed around the side wall except for at least one ventilating opening spaced oppositely from the nose-engaging portion of said eye-cup, said inner lens having a plurality of ventilating apertures located adjacent the periphery thereof and within the inner periphery of said rim member and the inner surface of said eye-cup and providing the only ventilating communication between the interior of said eye-cup and the air space between said spaced lenses, and a plurality of ventilating apertures arranged around the side wall of said rim means intermediate said lenses so as to provide vent openings from the outside into said air space.

2. In a goggle of the type described, a face conforming eye-cup, a rim member detachably secured to the front edge of the eye-cup, outer and inner lens positioned within said rim member, the inner lens being disposed against the

front edge of said eye-cup and the outer lens being disposed against lens retaining means adjacent the front edge of said rim, an annular spacer member disposed between said lenses adjacent the peripheries thereof, said eye-cup having at least one ventilating opening in the side thereof away from the nose-engaging portion, said inner lens having a plurality of ventilating apertures located adjacent the periphery thereof and within the inner periphery of said rim member and the inner surface of said eye-cup and providing the only ventilation between the interior of said eye-cup and the air space between said spaced lenses, and a plurality of ventilating apertures arranged around the side wall of said rim member so as to provide vent openings into said air space between said spaced lenses.
